US00D997554S

(12) **United States Design Patent** (10) **Patent No.:** **US D997,554 S**
Lu (45) **Date of Patent:** **** Sep. 5, 2023**

(54) **PROTECTIVE CASE FOR EARPHONE**

(71) Applicant: **Yehu Lu**, Chaohu (CN)

(72) Inventor: **Yehu Lu**, Chaohu (CN)

(**) Term: **15 Years**

(21) Appl. No.: **29/817,042**

(22) Filed: **Nov. 29, 2021**

(30) **Foreign Application Priority Data**

Aug. 5, 2021 (CN) 202130506565.8

(51) **LOC (14) Cl.** **03-01**

(52) **U.S. Cl.**

USPC **D3/302**

(57) **CLAIM**

The ornamental design for a protective case for earphone, as shown and described.

DESCRIPTION

FIG. 1 is a perspective view of a protective case for earphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the protective case for earphone where the protective case for earphone is in a configuration of use.

The broken lines in the drawings depict portions of the protective case for earphone that form no part of the claimed design.

1 Claim, 9 Drawing Sheets
